Inventor
Charles H. Bennett

By Stuart G. Barnes

Attorney

UNITED STATES PATENT OFFICE.

CHARLES H. BENNETT, OF DETROIT, MICHIGAN.

MANIFOLD AND CARBURETOR.

Application filed October 2, 1919. Serial No. 328,009.

To all whom it may concern:

Be it known that I, CHARLES H. BENNETT, a subject of the King of Great Britain, residing at Detroit, in the county of Wayne and 5 State of Michigan, have invented certain new and useful Improvements in Manifolds and Carburetors, of which the following is a specification.

This invention relates to intake tracks for 10 an internal combustion engine. Such a track in a multi-cylinder engine usually comprises a carburetor and a manifold.

It is quite a common practice to heat the 15 mixed air and fuel oil before it is introduced into the cylinders for the purpose of thoroughly vaporizing the fuel oil. This is especially necessary where a low grade of fuel oil, such as kerosene, is used.

A very common way of heating the mixture 20 is to pass some of the exhaust gases around the passage-way containing the mixed air and fuel oil. However, where the mixture is heated to a high degree to secure the best results in vaporization of the fuel 25 oil, this causes such an expansion as to limit the mass of combined air and fuel oil that can be accommodated in a cylinder. In short, the cylinder will not work to its capacity because the charge is rarefied by reason of 30 the high degree to which it has been heated.

It is the object of the present invention to secure the beneficial effect of heating for vaporization and at the same time, as near as may be, get the full power capacity of the 35 cylinder. This is achieved by mixing unheated air with the heated mixture between the heating means and the cylinder.

In most carburetors or mixing systems a 40 supply of air, called the "auxiliary," "secondary," or "compensating" air, is taken in for the purpose of furnishing more air without such air drawing out more fuel oil in a range of speed between low speed and a relatively high speed. This air does not pass 45 the fuel oil nozzle. Various means have been devised to provide this air, such as spring valves, devices for opening an air passage around the outside of a Venturi tube, or other means. It is the object of the 50 present invention to by-pass this compensating air uncharged with fuel oil around the heating means and deliver it to the intake track between the heating means and the cylinder. This unheated air mixing with the 55 oil-charged heated air does not have any appreciably disadvantageous effect upon the

vaporized fuel oil and very materially increases the density of the charge drawn into the cylinder. This, therefore, very materially increases the efficiency of the cylinder 60 over what would be the case where a highly heated mixture is drawn directly into the cylinder.

The throttle is placed in the intake track between the engine cylinder and the point 65 where the unheated and uncharged auxiliary air unites with the heated and oil-charged air. With the throttle in this position the auxiliary air may be by-passed in the way stated without in any way interfering with 70 the action of the carburetor.

In the drawings,—

Fig. 1 is a vertical irregular section of the carburetor taken on substantially the line 1—1 of Fig. 2.

Fig. 2 is a section of the carburetor taken on the line 2—2 of Fig. 1 and a front elevation of my manifold.

a designates the fuel chamber of the carburetor, which may be provided with a float 80 and the usual other appliances, not shown. *b* is a fuel nozzle which is here shown merely as a tube but which may be constructed in any desired way for adjustment or otherwise. The Venturi tube *c* is guided in vertical reciprocation by the guiding tube *d*. The Venturi tube has an external flange *e* which, when the engine is not operating or running at low speed, is adapted to rest upon the frusto-conical surface *g* and thereby 90 close the auxiliary air ports *f*. This flange is an auxiliary air valve and in connection with the frusto-conical walls *g* controls the admission of the "auxiliary," "secondary" or "compensating" air.

The inside of the Venturi tube is in the form of two cone frustums set end to end, the meeting line of the two frustums being the narrowest part of the interior of the tube. When the engine is not running the 100 narrow part is considerably below the orifice of the nozzle, but as the engine speeds up the Venturi tube is lifted by the suction. This brings the narrow portion of the tube more or less near the orifice of the fuel nozzle. 105 This increases the velocity of the air drawn up about the nozzle and through the tube and thereby materially increases the aspirating effect upon the fuel oil nozzle.

If all the air used in the cylinders were 110 drawn through the Venturi tube and around the fuel nozzle, this would overload the air

with fuel oil when the engine speeds up. As already explained, a passage-way for auxiliary air is provided through the ports *f* and on the outside of the Venturi tube. 5 The chamber between the tube and the frusto-conical walls is designated *h* and may be called the auxiliary air chamber. Ordinarily this auxiliary air is taken into the intake track at the end of the Venturi tube, 10 but in my construction the upper end of the Venturi tube *c* extends into and is guided by the passage-way *x* through the carburetor flange and thereby closes off the auxiliary air from passing into the manifold 15 at this point with the mixed air and fuel oil.

The manifold here shown is one that is heated by passing the exhaust gases from the exhaust passage-way *h* around the intake passage in the manifold. This intake passage is cored in the manifold and designated *n*. So called "hot pins" *o* run across this intake passage-way to provide a relatively large exposure of heated metal to the 25 mixture passing through the intake passage. This means for heating the mixed air and fuel oil is only an example of many ways either in the carburetor or manifold that may be adopted. The heated mixture of air 30 and fuel oil then passes into a neck *j* protruding from the body of the lower manifold and provided with a bolting flange *y*. Projecting downwardly from the neck portion *j* is a nipple *z* adapted to receive the by-pass pipe *i* which is secured in this nipple by 35 the combined gland and nut *s*. The other end of the by-pass pipe *i* is secured in the nipple *r* projecting from the side of the carburetor. The combined nut and packing 40 gland *t* secures this end of the by-pass pipe into the carburetor. The opening through this nipple *r* leads into the auxiliary air chamber *h*.

The lower manifold, as indicated in the 45 drawings, is essentially an exhaust manifold with the intake passage leading therethrough for the purpose of heating the mixed air and fuel oil. The neck *j* leads out of the side of this exhaust manifold 50 and consequently substantially out of the range of the intense heat of the exhaust manifold. Here at this point the by-pass pipe *i* delivers the uncharged and unheated auxiliary air to the heated and charged air 55 drawn through the exhaust manifold. This materially lowers the density and in actual practice it is found in no disadvantageous way to affect the vaporized condition of the fuel oil. The second manifold *l* is bolted 60 to the neck portion of the lower manifold by bolts which pass through the bolting flange *y* of the neck *j* and through a bolting flange on the stem of the upper manifold *l* which is essentially an intake manifold. In the stem of this manifold is placed

a throttle *m*. This throttle is between the point of the union of the unheated air and the cylinder. It is, therefore, in a position to govern both the auxiliary air passage and the passage of the mixed air and fuel oil 70 through the heating means.

The manifold is shown here as made up of two castings but obviously it could be made in other ways and still embody the broad principles of operation which are 75 comprehended in this invention.

What I claim is:

1. In an intake track for internal combustion engines, the combination of a carburetor having primary and auxiliary air arrangements therein and provided with an auxiliary air control operated by the primary air and the auxiliary air in connection with the engine suction, a passage-way leading from the carburetor to the engine cylinder for taking the mixed air and fuel oil from the carburetor, a heater for heating the mixed primary air and fuel oil, and a by-pass pipe for taking the auxiliary and uncharged air from the carburetor leading 85 to the said passage-way between the heater and the engine cylinder.

2. In an intake track for an internal combustion engine, the combination of a carburetor provided with an automatically-regulated air and fuel oil mixing apparatus and provided with an automatically-regulated compensating air apparatus, the said automatic regulation being affected by the compensating air in connection with the engine suction, a passage-way leading from the carburetor to the engine cylinder for taking the automatically-regulated mixture of air and fuel oil from the carburetor, a heater 90 for heating the mixture passing through said passage-way, and a by-pass pipe for taking the automatically-regulated compensating air from the carburetor before it is charged with fuel oil and leading it around 95 the heater and delivering it to said passage-way between said heater and the engine cylinder.

3. In an intake track for internal combustion engines, the combination of a carburetor provided with automatically regulated apparatus for mixing primary air and fuel oil and provided with apparatus controlled by the entire engine suction for admitting auxiliary air to the carburetor, a passage-way leading from the carburetor to the engine cylinder for taking the automatically regulated mixture of air and fuel oil, a by-pass pipe leading from the carburetor for taking the automatically regulated but 115 uncharged auxiliary air and by-passing it around the heater and delivering it to the said passage-way between the heater and the engine cylinder, and a throttle valve 120 located between the cylinder and the point 125 130

of union of the heated charged air and the unheated uncharged auxiliary air.

4. In an intake track for internal combustion engines, the combination of a carburetor provided with a Venturi tube and provided with an auxiliary air chamber about the Venturi tube having suitable automatic regulating means, the end of the Venturi tube being arranged to close the mixture passed through the Venturi tube off from the auxiliary air chamber, a passage-way leading from the end of the Venturi tube for taking the mixed air and fuel oil and leading the same to the engine cylinder, a heater for heating the mixed air and fuel oil passing out the Venturi tube, and a by-pass pipe for taking the auxiliary air from the auxiliary air chamber and leading it around the heater and delivering it to the passage-way between the said heater and the engine cylinder.

5. In an intake track for internal combustion engines, the combination of a carburetor, a manifold provided with an exhaust passage-way and an intake passage-way communicating with the carburetor and further provided with a hollow neck portion extending from the body of said manifold and communicating with the intake passage-way, and a by-pass pipe leading from the carburetor to take uncharged air and lead it around the heating portion of the manifold and deliver it to the passage-way in the said neck portion.

35 6. In an intake track for internal combustion engines, the combination of a carburetor, a manifold having an exhaust passage and an intake passage, the latter leading from the carburetor, the said manifold being further provided with a hollow neck portion projecting from the body of the manifold and communicating with the intake passage in the manifold, a by-pass pipe leading from the carburetor for taking uncharged air therefrom, by passing it around the heating portion of the said manifold, and delivering it to the neck portion of the manifold, a second manifold connecting with

the first manifold at the said neck, and a throttle valve located in the said second manifold.

7. The combination of a carburetor provided with an automatic air and fuel oil control, means for conveying the mixture from the carburetor to an engine, means for heating such mixture on its way to the engine, and means for by-passing around said heating means unmixed air drawn through the carburetor to operate on said automatic control and to introduce the said air to the heated mixture for the purpose of lowering its temperature and increasing its density.

8. The combination of a carburetor, a regulating device therefor raised and lowered by the engine suction, means for conveying the mixed air and fuel to the engine, means for heating the mixture on its way to the engine, and means for by-passing part of the air which operates upon the regulating device before it is mixed in the carburetor, said by-passing being around said heating means to mix the by-passed air with the heated mixture for the purpose of increasing the density thereof.

9. The combination of a carburetor provided with an air chamber, a Venturi tube on the inside of the chamber, a fuel nozzle contained within the Venturi tube, said air chamber provided with conical walls and the said Venturi tube being provided with a flange operating in connection with the conical walls to increase the air passage through the air chamber as the engine speeds up, a passage-way leading from the end of the Venturi tube to the engine cylinder, means for heating such passage-way to volatilize the mixture of fuel oil and air, and means for by-passing the air from the said air chamber past the said heating means for the purpose of mixing the cool unmixed air with the heated mixed air to increase the density thereof.

In testimony whereof I affix my signature.

CHARLES H. BENNETT.
